(57) **CLAIM**

The ornamental design for an electric hair removal device,
as shown and described.

DESCRIPTION

FIG. 1 is a perspective view of an electric hair removal device with a cap in accordance with the present invention;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of an electric hair removal device without a cap in accordance with the present invention;

FIG. 9 is a front view thereof;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is a perspective view of a cap for an electric hair removal device in accordance with the present invention;

FIG. 16 is a front view thereof;

FIG. 17 is a rear view thereof;

FIG. 18 is a right side view thereof;

FIG. 19 is a left side view thereof; and,

FIG. 20 is a top view thereof.

The invention pertains to an ornamental design for an article of manufacture. The broken lines illustrate portions of the electric hair removal device and form no part of the claimed design.
